UNITED STATES PATENT OFFICE.

OTTO THIEME AND FREDERICK OTTO MUELLER, OF ST. LOUIS, MISSOURI, ASSIGNEES TO
MOON-HOPKINS BILLING MACHINE COMPANY, OF ST. LOUIS, MISSOURI, A CORPO-
RATION OF MISSOURI.

PRESSURE-ROLIER FOR TYPEWRITING-MACHINES, &c.

1,336,797.

Specification of Letters Patent.

Patented Apr. 13, 1920.

Application filed August 16, 1917. Serial No. 186,475.

To all whom it may concern:

Be it known that we, OTTO THIEME and FREDERICK OTTO MUELLER, citizens of the United States, residing at the city of St. Louis, State of Missouri, have invented a certain new and useful Improvement in Pressure-Rollers for Typewriting-Machines, &c., of which the following is a full, clear, and exact description, such as will enable others skilled in the art to which it appertains to make and use the same, reference being had to the accompanying drawings, forming part of this specification, in which—

15 Figure 1 is a detail view of the axle or bar on which the pressure rollers are mounted.

Fig. 2 is a detail view of the pressure roller and its associate parts in their dis-
20 assembled relation.

Fig. 3 is a vertical cross sectional view showing a pressure roller as applied to the platen on an ordinary typewriting machine.

25 Figs. 4, 5, and 6 are diagrammatic views illustrating the independent adjustment of the frames.

This invention relates to a new and useful improvement in pressure rollers for typewriting machines, the object being to construct a roller of the character described which is easily adjustable and cheaply manufactured and one which will exert with its 30 companions a uniform pressure on the paper carried by the platen regardless of the thickness of the paper at different points along the length of the platen. The roller is made up in sections, each section of which is independently adjustable and in combined 35 adding and typewriting machines where there is a split platen, i. e., a platen divided into sections each of which is capable of independent rotation for receiving papers of different thicknesses, such as may be employed in making out invoices, ledger sheets and the like, our improved pressure roller is especially adaptable.

In the drawings 1 indicates the frame of 40 a laterally movable paper carriage; 2 is the platen arranged therein; 3 is a rod or shaft mounted in suitable bearings at each end whereby the same may be moved toward and away from the platen. These means are not

shown in the drawings as they form no part 55 of our present invention. This shaft is provided with a number of threaded openings 4 for receiving screws 5. 6 is a frame piece preferably made of pressed metal having perforated lugs or ears 7 by which it is 60 strung on the shaft 3. This frame plate also has perforated lugs or ears 8 in which is mounted a pressure roller 9, said pres- 65 sure roller preferably having a removable shaft 10 threaded at one end to receive a 65 nut 11 by which the roller is held in position in the frame.

12 indicates a flat leaf spring bent substantially in the form of an S one end of which is slotted at 13 to receive the screw 5. 70 In assembling the parts, the sections of the pressure roller are preferably mounted in their respective frames after which the frames are strung on the shaft and the 75 springs arranged in position. The screws are then passed through the slots in the springs and into the threaded openings in the shaft and turned down until the frames are approximately in their proper position. The shaft is now mounted in its bearings 80 and the parts are finally adjusted by turning the screws tightly home to lock the frames in their final position. Each section of the pressure roller is thus capable of in- 85 dependent adjustment and by moving the frame and the S-shaped spring about the shaft as much or as little pressure may be placed on the sections of the pressure roller as is desired. An advantageous feature of 90 these independently adjustable sections lies in the adaptability of the shaft to accommo- 95 date itself to the different thicknesses of the paper at different points along the length of the platen because the sections of the pressure roller, even though not accurately adjusted, will adapt themselves to the different thicknesses of the paper and each pressure roller section will exert uniform 100 pressure on the paper or different thicknesses of paper.

In Figs. 4, 5, and 6, we have diagrammatically illustrated the independent adjustment of the frames incident to the adjustment of the spring 12 on rod 3. In these views we 105 have illustrated, in an exaggerated manner, sheets of paper *a*, there being three of said sheets shown in Fig. 4, two in Fig. 5, and

one in Fig. 6, which may represent different independently rotatable sections of the split platen.

By referring to Fig. 4, it will be observed 5 that by adjusting the spring on the rod so that the screw is located at the bottom of the slot, the frame will be permitted to drop down, thus permitting the thick sheet or sheets of paper to be arranged in position 10 under the platen and the proper pressure exerted thereon by the pressure roller.

By adjusting the spring, as shown in Fig. 5, wherein the screw is located midway the slot, the frame will be adjusted upwardly so 15 that the proper pressure will be exerted on the thinner sheet or sheets of paper, where as in Fig. 6, we have shown the screw arranged on the rod in such manner that the screw is located in the upper end of the 20 slot in which the frame will be further lifted so as to insure the roller exerting the proper pressure on the thin sheet or sheets of paper passing under the platen.

In this manner, the frames are independently adjustable to accommodate different 25 thicknesses or numbers of sheets of paper against which the pressure roller will exert the proper amount of pressure.

What we claim is:

30 1. A pressure roller comprising a shaft, a frame mounted on said shaft and capable of pivotal movement thereon, a roller carried by said frame, a slotted flat spring mounted on said shaft and designed to co

operate with said frame, and means for adjusting the tension of said spring, said means comprising screws passing through said slot and into the shaft.

2. A pressure roller composed of sections each section being mounted in a frame, a shaft on which all of said frames are strung, and means varying the tension of each individual spring, whereby variable tension on each frame may be secured.

3. A pressure roller comprising a shaft, 45 frames strung on said shaft and having independent pivotal movement thereabout, pressure roller sections mounted in said frames, springs for exerting variable tension on said frames; means for independently adjusting each spring, and means for holding said springs in their adjusted position.

4. In a pressure roller, the combination of a shaft, a frame pivotally mounted on said shaft, a pressure roller section carried by said frame, and a slotted S-shaped spring mounted on the shaft to exert a variable tension 55 on said frame and to prevent longitudinal displacement of the frame on the shaft, and means for adjustably holding said spring on said shaft against rotary and longitudinal displacement.

In testimony whereof we hereunto affix our signatures, this 24th day of July, 1917. 65

OTTO THIEME.

FREDERICK OTTO MUELLER.
